FISHING LURE

Vincent A. Graham, Rte. 1, Salem, S. Dak.

Filed June 30, 1965, Ser. No. 85,970

Term of patent 14 years

(Cl. D31—4)

FIG. 1 is a perspective view of a fishing lure showing my new design;

FIG. 2 is an enlarged elevation thereof with portions omitted for convenience of illustration;

FIG. 3 is a modified form of the fish lure shown in FIG. 1; and

FIG. 4 is an enlarged elevation thereof, with portions omitted for convenience of illustration.

The broken lines are shown for illustrative purposes only.

I claim:

The ornamental design for a fishing lure, as shown and described.
